TRACK LUBRICATING APPARATUS

Wallace M. Gray, Cincinnati, Ohio

Application March 27, 1931, Serial No. 525,709

14 Claims. (Cl. 184—3)

My invention relates to improvements in track lubricating apparatus. One of its objects is to provide an improved track lubricating apparatus in which the flanges of the car wheels 5 do not normally contact with metal or other parts of the lubricant supply or feeding apparatus, and in which a stiff or semi-solid lubricant is fed to and built into projections or ridges above the lubricant supporting and feeding apparatus and against the side face of the head 10 of the rail in position to make contact with the side and throat of the wheel flanges and be thereby taken up and distributed along the curved or other sections of the rail requiring lubrication. Another object is to provide lubricant supporting and feeding apparatus substantially as above outlined in which a yielding lubricant supporting member is provided which is out of contact with normal wheel flanges, but which 15 in the event of being engaged by the abnormally deep flanges of worn car wheels, or by other downwardly extending member, is enabled to yield and move downwardly out of the path of such abnormal wheel flange or other obstruction 20 and thereby avoid injury to either the lubricating apparatus or the wheel flange, and in which the downwardly moving lubricating member will automatically return to normal position and function in its usual manner. Another object is 25 to provide for the convenient and reliable support and application of the lubricating apparatus and its components relative to the rail. Another object is to provide apparatus adapted to apply lubricant to the side of the rail head and 30 throat of the wheel flanges with a minimum amount of splashing of lubricant to other localities, particularly by the passage of trains at high rates of speed. My invention also comprises certain details of form and arrangement 35 and combination of components, all of which will be fully set forth in the description of the accompanying drawing, in which;

Fig. 1 is a plan view of a section of railway rail with my improved track lubricating apparatus applied thereto.

Fig. 2 is a side elevation of the same.

Fig. 3 is a vertical section taken on line 3—3 of Fig. 2.

Fig. 4 is a view similar to Fig. 3.

Heretofore the car wheel flanges were arranged 50 to strike metal to metal some part of the track lubricating apparatus to feed or distribute the lubricant to the desired locality. Where the trains are moving at high rates of speed one type of apparatus has best served the purpose of applying lubricant to the rails, while with the trains traveling at relatively slower rates of speed, apparatus of another type has best served the purpose, and in either type the frequent contact of 55 the wheel flanges, metal to metal with lubricant members, has developed objections. Changes in weather conditions and temperatures also have important influences upon the operation of the lubricating apparatus. My present apparatus obviates frequent metal to metal contacts, and many 60 of the objectionable features of apparatus heretofore employed for track lubrication.

The accompanying drawing illustrates one embodiment of my invention in which 16 represents a section of railway rail, to which is rigidly attached a cast housing member 17, by means of a series of bolts 18 passed through perforations in the web 19 of the rail and secured in place by means of nuts 20. The housing member 17 has a detachable front plate 21 attached thereto by means of bolts 22. The housing 17 has a ledge 23 and the plate 21 has a similar ledge 24, which face each other with an intervening channel. An inverted U-shaped channel bar 25 is seated in the channel between the ledges 23 and 24, and has laterally extending ribs 26 and 27, which extend beneath the ledges 23 and 24 and limit the movement upwardly of the channel bar 25. The channel bar 25 is resiliently supported in position with the ribs 26 and 27 normally engaging the 70 ledges 23 and 24 by means of a series of mushroom shaped spring actuated plungers 28, the stems 29 of which are supported and move vertically within the bores of cylindrical projections 30 attached to the housing member 17. Coiled springs 31 encircle the projections 30 and bear at their lower ends against the housing member 17, and at their upper ends against the under faces of the plunger heads 28. The upper face of the channel bar 25 is out of the path of normally positioned car 75 wheel flanges but may be engaged and depressed by the deeper flanges of worn car wheels.

A main lubricant conduit 32 extends nearly the entire length of the housing member 17 and is provided with branch lubricant conduits 33 adapted to direct lubricant to position above the channel bar 25, and close to the side face of the rail head, where the lubricant, being preferably of high viscosity and semi-solid builds itself up in a continuous ridge or series of short ridges along the 80 side face of the rail head and between the rail head and the crown of the channel bar 25, as shown in Fig. 4 where it is in position to be contacted with by the wheel flanges 42 of passing car wheels in such manner as to crowd the lubricant against the side face of the rail head and cause the lubricant to reach the throat of the wheel flange, from which position the lubricant is distributed by the wheel flanges along the 85 upper portion of the side of the rail head as far as the curve in the rail extends. The upper face of the housing member 17 is low enough to be out of the path of any car wheel flange, and the crown of the channel bar 25 is low enough so as to be out of the path of any normal car wheel 90

- flange, and free to yield downwardly if engaged by the flange of a worn car wheel. Thus practically all of the car wheel flanges pass along the rail and press the lubricant against the side face of 5 the rail head causing the lubricant to reach the throat of the flange and have lubricant applied to the throat thereof without a metal to metal contact between the car wheel flanges and the channel bar 25 or other portion of the lubricant distribution apparatus. 10 Lubricant is fed into the main lubricant conduit 32 through a flexible conduit 40, leading from any suitable lubricant pump or other lubricant feeding apparatus, as for instance an intermittently actuated lubricant pump located beneath the rail or in position to be actuated by the rhythmic vertical movement of the rail due to the passage of rolling stock along said rails. 15 The apparatus herein shown and described is 20 capable of considerable modification within the scope of the claims without departing from the spirit of my invention.
- What I claim is:
1. Track lubricating apparatus comprising a lubricant supporting and distributing member supported rigidly relative to one of a pair of rails in position to distribute and build up a body of semi-solid lubricant along one side face of the rail head in position for said lubricant to be engaged by the flanges of passing car wheels and distributed thereby along the side face of the rail, said supporting and distributing member being below and out of position to contact with the flanges of normal car wheels. 25
  2. Track lubricating apparatus comprising a lubricant supporting and distributing member supported rigidly relative to one of a pair of rails in position to distribute and build up a body of semi-solid lubricant resting against one side face 30 of the rail head and upon said supporting and distributing member in position for said lubricant to be engaged by the flanges of passing car wheels and fed thereby to the upper limits of the side face of the rail head and to the throat of the flange and thence distributed by the flanges along the side face of the rail, said supporting and distributing member being out of contact with the flanges of normal car wheels. 40
  3. Track lubricating apparatus comprising a lubricant supporting and distributing member provided with a lubricant supply conduit supported rigidly relative to a rail in position to distribute and build up a body of semi-solid lubricant along one side face of the rail head and upon 45 said supporting and distributing member in position for said lubricant to be engaged between the side face of the rail head and the flanges of passing car wheels and forced thereby to the upper limits of the side face of the rail head and to the throat of the flanges and thence distributed by the flanges along the side face of the rail, said supporting and distributing member being below and out of position to contact with the flanges of normal car wheels. 50
  4. Track lubricating apparatus comprising a lubricant supporting and distributing member provided with a lubricant supply conduit supported rigidly relative to one of a pair of rails in position to distribute and build up a body of 55 semi-solid pressure-fed lubricant along one side face of the rail head and upon said supporting and distributing member in position for said lubricant to be engaged between the side face of the rail head and the flanges of passing car wheels and forced thereby to the upper limits of the side 60 face of the rail head and to the throat of the flanges and thence distributed by the flanges along the side face of the rail, said supporting and distributing member being below and out of position to contact with the flanges of normal car wheels. 65
  5. Track lubricating apparatus comprising a lubricant supporting and distributing member provided with a lubricant supply conduit supported rigidly relative to one of a pair of rails in position to distribute and build up a body of semi-solid pressure-fed lubricant along one side face of the rail head and to the throat of the flanges and thence distributed by the flanges along the side face of the rail, said supporting and distributing member being below and out of position to contact with the flanges of normal car wheels. 80
  6. Track lubricating apparatus comprising a lubricant supporting and distributing member supported rigidly relative to a rail, said supporting member having a lubricant supporting ledge extending outwardly from the lower portion of the side face of the head of the rail to which said supporting member is attached and out of the path of travel of passing car wheel flanges, a main lubricant channel substantially parallel to the rail, and lateral upwardly directed branch lubricant conduits adapted to discharge and build up lubricant upon said ledge and against the side face of the rail head in position to contact with the sides and throats of passing car wheel flanges. 85
  7. Track lubricating apparatus comprising a lubricant supporting and distributing member supported rigidly relative to one of a pair of rails, said supporting member having a lubricant supporting ledge extending outwardly from the lower portion of the side face of the head of the rail to which said supporting member is attached and out of the path of travel of passing car wheel flanges, a main lubricant channel substantially parallel to the rail, and lateral upwardly directed branch lubricant conduits adapted to discharge and build up lubricant upon said ledge and against the side face of the rail head in position to contact with the sides and throats of passing car wheel flanges and a vertically movable ledge section attached to and vertically movable relative to said lubricant supporting member said vertically movable ledge section being located adjacent to said stationary ledge section in spaced relationship with the rail head. 90
  8. Track lubricating apparatus comprising a lubricant supporting and distributing member comprising a rigidly mounted section and a resiliently mounted section, said rigidly mounted section being rigidly attached to a rail and provided with a stationary lubricant supporting ledge extending outwardly from the lower portion of the side face of the head of the rail and a lubricant supply conduit having lubricant discharge ports upwardly through said stationary ledge section to build up a body of lubricant upon said stationary ledge section and against the side face of the rail, and said resiliently mounted section 95

being supported by and outside of said rigidly mounted section and ledge and projecting above the face of said stationary ledge section to assist in retaining the lubricant in position upon said stationary ledge section and in contact with the side face of the rail head.

9. Track lubricating apparatus comprising a lubricant supporting and distributing member supported rigidly relative to one of a pair of rails, 10 said supporting member having a lubricant supporting ledge extending outwardly from the lower portion of the side face of the head of the rail to which said supporting member is attached and out of the path of travel of passing car wheel flanges, a main lubricant channel substantially parallel to the rail, and lateral upwardly directed branch lubricant conduits adapted to discharge and build up lubricant upon said ledge and against the side face of the rail head in position 20 to contact with the sides and throats of passing car wheel flanges, and a vertically movable ledge section vertically movable relative to said lubricant supporting member said vertically movable ledge section being located adjacent to said stationary ledge section in spaced relationship with the rail head.

10. Track lubricating apparatus comprising a lubricant supporting and distributing member comprising a rigidly mounted section and a resiliently mounted section, said rigidly mounted section being rigidly attached to a rail and provided with a stationary lubricant supporting ledge extending outwardly from the lower portion of the side face of the head of the rail and a lubricant supply conduit having lubricant discharge ports upwardly through said stationary ledge section to build up a body of lubricant upon said stationary ledge section and against the side face of the rail, and said resiliently mounted section being supported outside of said rigidly mounted section and ledge and projecting above the face of said stationary ledge section to assist in retaining the lubricant in position upon said stationary ledge section and in contact with the side face of the rail head.

11. Track lubricating apparatus comprising a longitudinal lubricant supporting and distributing member including a lubricant supply conduit, means for mounting said member stationarily and in close proximity with one of a pair of rails, in position to support and build up a body of semi-fluid pressure-fed lubricant along one side face of the rail head for said lubricant to be engaged between the side face of the rail head and the flanges of passing car wheels, the lubricant being forced thereby to the upper limits of the side face of the rail head and to the throat of the flanges and thence distributed by the flanges along the side face of the rail, a resilient longitudinal lubricant supporting floor section substantially coextensive with the said stationarily supported member and extending slightly above said stationarily supported member in close proximity therewith alongside the rail head to form a longitudinal trough for lubricant adjacent to the side face of the rail, said stationary and resilient parts being below and out of contacting position with the flanges of normal car wheels.

12. Track lubricating apparatus comprising in combination, a longitudinal housing member including a main lubricant conduit to be supplied with lubricant under pressure, an upper portion

on said member having branch conduit means in fluid communication with the main lubricant conduit, means fixing said longitudinal housing member along the gauge side of a railway rail in substantial parallelism therewith and with said upper portion disposed substantially beneath the rail head and the branch conduit means directed outwardly below the adjacent side face of the rail head, a longitudinal resilient lubricant supporting member substantially coextensive in length with said housing member and means for mounting the resilient member in parallelism with and adjacent to the rail head side and to the upper portion of the longitudinal housing member, to support lubricant ejected thereon by the branch conduit means, said resilient member being below and out of contacting relationship with the flanges of normal car wheels passing along the rail, and an upwardly and outwardly inclined top portion on the longitudinal resilient lubricant supporting member, adjacent to the rail head, providing with the rail head a trough for holding lubricant and urging said lubricant to gravitate toward the rail head.

13. Track lubricating apparatus comprising in combination, a longitudinal housing member including a main lubricant conduit to be supplied with lubricant under pressure, an upper portion on said member having branch conduit means in fluid communication with the main lubricant conduit, means fixing said longitudinal housing member along the gauge side of a railway rail in substantial parallelism therewith and with said upper portion disposed substantially beneath the rail head and the branch conduit means directed outwardly below the adjacent side face of the rail head, a longitudinal resilient lubricant supporting member substantially coextensive in length with said housing member and means for mounting the resilient member in parallelism with and adjacent to the rail head side and to the upper portion of the longitudinal housing member, to support lubricant ejected thereon by the branch conduit means, said resilient member being below and out of contacting relationship with the flanges of normal car wheels passing along the rail.

14. Tracking lubricating apparatus comprising in combination, a longitudinal housing member including a main lubricant conduit to be supplied with lubricant under pressure, an upper portion on said member having branch conduit means in fluid communication with the main lubricant conduit, means fixing said longitudinal housing member along the gauge side of a railway rail in substantial parallelism therewith and with said upper portion disposed substantially beneath the rail head and the branch conduit means directed outwardly below the adjacent side face of the rail head, a longitudinal resilient lubricant supporting member substantially coextensive in length with said housing member and means for mounting the resilient member in parallelism with and adjacent to the rail head side and to the upper portion of the longitudinal member, to support lubricant ejected thereon by the branch conduit means, and an upwardly and outwardly inclined top portion on the longitudinal resilient lubricant supporting member, adjacent to the rail head, providing with the rail head a trough for holding and urging said lubricant to gravitate toward the rail head.
